CHILD'S SCRUB BRUSH

Joseph W. Mayer, Troy, N. Y., assignor to Auto-graf Brush & Plastics Co., Incorporated, a corporation of New York

Application September 5, 1952, Serial No. 21,349

Term of patent 14 years

(Cl. D9—2)

To all whom it may concern:

Be it known that I, Joseph W. Mayer, a citizen of the United States, residing at Troy, in the county of Rensselaer, State of New York, have invented a new, original, and ornamental Design for a Child's Scrub Brush, of which the following is a specification, reference being had to the accompanying drawing, in which:

Fig. 1 is a plan view of a child's scrub brush incorporating the new design;

Fig. 2 is a side elevational view thereof;

Fig. 3 is a front end elevational view thereof;

Fig. 4 is a rear end elevational view thereof;

Fig. 5 is a bottom plan view thereof;

Fig. 6 is a longitudinal vertical section of the brush shown in Fig. 1; and

Fig. 7 is a transverse vertical section on line 7—7 of Fig. 6.

The dominant features of my design reside in those portions shown in full lines.

I claim:

The ornamental design for a child's scrub brush, as shown and described.

JOSEPH W. MAYER.
